UNITED STATES PATENT OFFICE.

SALLIE M. TAYLOR, OF ST. LOUIS, MISSOURI.

CATAMENIAL GARMENT.

972,248.

Specification of Letters Patent. Patented Oct. 11, 1910.

Application filed March 4, 1910. Serial No. 347,356.

To all whom it may concern:

Be it known that I, SALLIE M. TAYLOR, citizen of the United States, residing at St. Louis, State of Missouri, have invented certain new and useful Improvements in Catamenial Garments, of which the following is a full, clear, and exact description, reference being had to the accompanying drawings, forming a part hereof.

- 10 My invention has relation to improvements in catamenial garments; and it consists in the novel details of construction more fully set forth in the specification and pointed out in the claim.
- 15 In the drawings, Figure 1 is an outline in side elevation of a human body showing my invention applied thereto; Fig. 2 is a plan view of the garment unfolded; Fig. 3 is a plan with waist-band sections in coupled relation; Fig. 4 is a plan of the garment in its folded position as actually worn; and Fig. 5 is an enlarged sectional detail on the line 5—5 of Fig. 2.

The object of my invention is to provide a 20 catamenial garment which may be readily applied; one which is water-proof, soft, pliable, easily adjusted and convenient to wear; and one possessing further and other advantages better apparent from a detailed description of the invention which is as follows:—

Referring to the drawings, B. represents the outline of a portion of the human body to which the garment is applied. The garment comprises a back section 1 preferably made of two thicknesses or layers of fabric (Fig. 5) such as sateen or the like, stitched along the edges, the free edge of said back section being provided with waist-band sections 2, 2' respectively provided with a button *a* and button-hole *b* respectively by which they may be fastened around the waist. The band section 2' is provided with a central tongue 3 for a purpose presently to appear. Secured to the back section 1 is the front or catamenial section 4, preferably of water-proof material such as oil-silk, the free end of said section terminating in a tongue 5 which when folded (Figs. 1, 4) 45 may be secured to the tongue 3 by a safety-

pin *c*. Along the seam between the sections 1 and 4 are disposed a series of elastic loops or strips 6 each carrying a ring 7 for the support of a safety-pin *d*, the latter being used to secure the rear end of a towel *T* supported by the section 4, the front edge of the towel being likewise secured by a pin *d* passed through a ring 7 carried by an elastic strip 6 sewed to the section 4 adjacent the tongue 5. The towel *T* is thus supported 60 by a water-proof section 4 and being fastened to elastic strips such as 6 readily yields to any movements of the body and may be readily adjusted. It may be instantly removed by the unpinning of the safety pins 65 *d* and a fresh towel substituted, with no inconvenience whatever. To prevent the rear row of strips 6 pressing against the body of the wearer, I provide a protecting cushioning strip of fabric 8 of any soft material 70 sewed only along its upper edge, the lower or front edge being free as shown (Fig. 5). The tapering character of the section 4 and the towel carried thereby allows the same to be properly applied without inconvenience 75 to the wearer.

Having described my invention, what I claim is:—

A catamenial garment comprising a back section composed of two layers of fabric, a front catamenial water-proof section secured between the front edges of the layers of the back section, a waist-band carried by the free end of the back section and provided with a central tongue, a tongue terminating 85 the free end of the catamenial section, a series of elastic strips fastened at one end along the juncture between the sections, a protecting cushioning strip secured over the elastic strips, an elastic strip at the free end 90 of the catamenial section, and means carried by the elastic strips for securing a towel in position over the catamenial section, substantially as set forth.

In testimony whereof I affix my signature, 95 in presence of two witnesses.

SALLIE M. TAYLOR.
